MOLDS FOR RUBBER SOLED FOOTWEAR

Fred Farmer and Andrew Szerenyi, Waynesville, N. C., assignors to Ro-Search, Inc., Waynesville, N. C., a corporation of North Carolina

Application May 13, 1952, Serial No. 287,536

4 Claims. (Cl. 18—34)

The invention refers to molds as used for the manufacture of shoes with soles containing rubber. Such molds commonly comprise a last to carry the upper, a frame to shape the outside rim of the sole, and a sole plate to shape the bottom surface of the sole. If the sole is made of dense and stiff rubber, the mold is closed and the rubber molded in a hydraulic press or by other power means. If the sole is made of porous rubber, it is customary to close and lock the mold by hand using a locking device which is part of the mold.

One object of the invention is to improve molds so that it becomes possible to manufacture footwear with a side rim of dense rubber without the use of costly hydraulic presses.

Another object of the invention is to improve the mold to permit the molding of rubber to uppers of heavy leather or other less flexible material, which hitherto could not be removed from the heated metal lasts of the common molds.

Other objects and characteristics of the invention are clarified in connection with the drawings, which show in Fig. 1 a schematic side view of a mold according to the invention, while Figs. 2 and 3 show in larger scale the last, forming part of the mold of Fig. 1, in the closed and open position respectively.

The mold shown in Fig. 1 consists of a base plate 1 carrying a bottom plate 2 with a protrusion 18 shaped to form the bottom surface and the inside surface of the side rim of the sole. The outside surface and the upper surface of the welt or side rim is shaped by the frame 4 with the lip 19, usually split lengthwise to facilitate demolding of the sole. A frame holder 5 holds the parts of the frame 4 together and is supported by springs 17. The last 6 can be placed upon the frame 4. A locking arm 11 is fastened with the hinge 15 to the base plate 1, which also carries through a hinge 14 a locking loop 12, held in the locking position by a knob 13 of the arm 11. That arm carries a pressure screw 9, which can be actuated by the handwheel 10 so as to transmit pressure through the plate 8 and the adjusting screws 16 to the top 7 of the last 6. The last 6 is divided in such manner that a relatively small part of the heel and the so-called quarter can be moved, as shown in Fig. 3, by a toggle lever arrangement 24, 25 fastened to the projections 22 and 23 of the heel part and the main part of the last respectively. The surface separating the heel part 21 from the main part of the heel has the geometric shape of a cylinder with the center line 26 located at the instep of the last. This is essential not only because it permits effective shortening of the last while in the upper, but also because it permits good fit along the dividing surface and with it good heat transfer from the heated main part of the heel to the part 21.

To use the old described above, material to form a solid rubber side rim or welt, such as a vulcanizable rubber mix, is placed into the corner formed by the bottom plate 2 and the frame 4. The upper is placed on the foreshortened last 6, the toggle 25 closed and thereby the upper

2

brought into the desired shape, so that it can be located against the lip 19 of the frame 4. The arm 11 then is moved into the position shown in Fig. 1 and the locking arm 12 will hold it there. By turning the handwheel 10 the last 6 with the upper is moved downwards, first against the frame 4 until a tight seal is obtained between the lip 19 and the upper. As the movement of the last continues against the resistance of the springs 17, the upper together with the frame 4 moves against the rib 18 and molds the rubber mix against the upper. As pressure is exerted only in the area of the side rim or welt, the hand operation of the wheel 10 is sufficient to obtain high specific pressure per square inch and correspondingly good molding and perfect adherence of the rubber to the upper.

Any surplus of rubber may escape in the direction of the movement of the last through a gap 27, between frame 4 and bottom plate 2 of between the rib 18 and the shoe bottom.

The insert 20 located in the bottom plate 2 might be removed if only a side rim or a welt of solid rubber is desired and the sole or mid-sole is to be applied in a later operation. Very often it is of advantage to leave the insert 20 in the position shown, and to fill the space between the insert and the shoe bottom with a mix for a porous sole. Such mix will mold and vulcanize without any outside pressure. The shoe, removed from the mold after the vulcanization will be ready for the application of a tread-sole. While the rib 18 is shown as an integral part of the bottom plate 2, it might be of advantage for certain types of shoes to make the rib 18 a separate piece to limit the inside surface of the welt or side rim. Such separate piece might be still a permanent part of the mold or might be a pressure resistant, stiff strip of material which becomes part of the sole.

The mold according to the invention is not only for the molding of natural rubber but also for any other natural or synthetic elastomer or rubber like qualities. The last as described above will be useful not only for the molding of side-rims or welts only but also for the molding of full soles as it permits the combination of high strength and uniform heating with the advantages of a fore-shortenable last. As can be seen in Fig. 3 and Fig. 3 the main part of the last can easily accommodate enough electric heating elements 28 to secure adequate and uniform heating. As further improvement the bottom surface of the last is formed by removable pieces 29 and 30, located in the last by pins 31 and held by set-screws 32 pressing against the preferably tapered pins. The sole surface of the last is correspondingly un-interrupted and smooth so as to avoid unsightly markings on the insole during the molding. If the pattern of the upper changes, it is sufficient to replace the parts 29 and 30, without replacing and re-adjusting the whole last.

What we claim is:

1. A mold for the molding and vulcanization of rubber in situ to a shoe upper, comprising a last to carry said upper, a frame to form the top and side surface of a welt, and a bottom plate, means to separate the inside of said welt from the center of the sole, said means comprising a projection uniformly spaced inside of the molding frame around the periphery of said sole, and means to exert pressure upon the rubber mass confined between said frame and said projection.

2. A mold for the molding and vulcanization of rubber in situ to a shoe upper, comprising a last to carry said upper, a frame to form the top and side surface of a welt, and a bottom plate, means to separate the inside of said welt from the center of the sole, said means comprising a projection uniformly spaced inside of the molding frame around the periphery of said sole, and means to exert pressure upon the rubber mass confined between said

frame and said projection, said last divided into a main part and a heel part along a cylindrical surface extending from the upper end of the rear quarter to the heel bottom, having its geometrical centerline near the instep of said last so as to present in the closed position of the last a continuous sole surface.

3. A mold for the molding and vulcanization of rubber in situ to a shoe upper, comprising a last to carry said upper, a frame to form the top and side surface of a welt, and a bottom plate, means to separate the inside of said welt from the center of the sole, said means comprising a projection uniformly spaced inside of the molding frame around the periphery of said sole, and means to exert pressure upon the rubber mass confined between said frame and said projection, said last divided into a main part and a heel part, said parts connected to each other by toggle levers which fore-shorten said last when open and in their closed position hold said parts to present a continuous sole surface.

4. A mold for the molding and vulcanization of rubber in situ to a shoe upper, comprising a last to carry said upper, a frame to form the top and side surface of a welt, and a bottom plate, means to separate the inside of

said welt from the center of the sole, said means comprising a projection uniformly spaced inside of the molding frame around the periphery of said sole, and means to exert pressure upon the rubber mass confined between said frame and said projection, said last divided into a main part and heel part movable in relation thereto and carrying a replaceable sole plate offering a smooth surface towards the insole and held by pins entering the main body of said last.
